UNITED STATES PATENT OFFICE.

CASIMIR F. NEEB, OF S. E. 1/4 SECTION 22, TOWNSHIP 139, BILLINGS COUNTY, NORTH DAKOTA.

DIRIGIBLE-HEADLIGHT SUPPORT.

1,191,720.

Specification of Letters Patent. Patented July 18, 1916.

Application filed January 28, 1916. Serial No. 74,765.

To all whom it may concern:

Be it known that I, CASIMIR F. NEEB, a citizen of the United States, and a resident of S. E. 1/4 section 22, township 139 N., range 5 100 W., 5 P. M., in the county of Billings and State of North Dakota, have invented a new and Improved Dirigible-Headlight Support, of which the following is a full, clear, and exact description.

10 My invention relates to the type of automobile lamp-supporting means in which provision is made for turning the lamps as the steering knuckles are turned so that the lamps will always be disposed toward the 15 direction of traveling.

An object of my invention is to provide lamp-supporting means of the class referred to adapted to be readily applied to an automobile without changing the construction of 20 the latter.

The invention also has for its object to provide lamp-supporting means of the indicated character improved in various particulars with a view to provide a simple construction and reliability in operation.

The invention will be particularly explained in the specific description following.

Reference is to be had to the accompanying drawings forming a part of this specification in which similar reference characters indicate corresponding parts in all the views.

Figure 1 is a side elevation of a lamp-supporting means embodying my invention, showing the same applied to an automobile; 35 Fig. 2 is a front view thereof, showing the improved lamp-supporting means on each side of the automobile; Fig. 3 is a sectional plan view, the section being taken on the line 3—3, Fig. 1; Fig. 4 is a detail in longitudinal vertical section on the line 4—4, Fig. 3; Fig. 5 is a detail in transverse vertical section and on an enlarged scale, the section being taken on line 5—5, Fig. 3; and Fig. 6 is an inverted sectional plan view on 45 the line 6—6, Fig. 5.

My invention is shown applied to a known form of automobile, the numeral 10 indicating the front axle, 11, the steering knuckles, 12 the knuckle arms, and 13, the cross-connecting rod of the knuckle arms.

My improved lamp-supporting and turn-

ing means include fixtures 14 having forked upper ends to receive the connecting rod 13. The said fixtures are used in a pair, one for each lamp, and they are received between 55 collars 15 shrunk on the cross-connecting rod 13 so that a movement of the said rod in either direction will carry with it, the said fixtures 14. Each fixture includes also a bearing block 16 received between the fork 60 of the said fixture at the upper side of the rod 13. Transverse bolts 17, passing through the said forks and through the block 16, serve to secure the fixtures in place, the bolts having suitable nuts 18.

To the forward side of each fixture 14, one end of a link 20 is connected by a horizontal pivot 19, said link extending forwardly and having its opposite end connected by a vertical pivot 21 to the rear end of an arm 22, 70 said arm having a sleeve 23, which is received on the squared lower end 24 of the upright lamp-rod 25. A set screw 26, in the sleeve 23, serves to fixedly secure the arm 22 in position on the lamp rod 25.

I provide separate means attachable to the vehicle spring and to the chassis respectively, whereby the lamp rod 25 is permitted turning movement to turn the lamp and permitted vertical movement in response to the 80 relative movements of the springs and chassis, said separate means being as follows: The rod 25 extends through a vertical sleeve 27 which is secured, by a clip 28, to the vehicle spring 29, the said clip receiving the 85 spring laterally and being fastened by bolts 30, or the like. The lamp rod 25 is vertically slidable also in a sleeve 31 above the sleeve 27, to the lower end of which sleeve 31, a nut or collar 32 is threaded, the collar being made fast to said sleeve by a set screw 33, or equivalent means. The rod 25 is round as at 25^a where it takes the sleeve 27 and has vertical corrugations at the periphery above said round part. Said corrugations of rod 90 25, have engagement with the sleeve 31 or its collar 32, or both, to cause a turning of the said sleeve when the said rod is turned, the collar being corrugated in the example shown. The sleeve 31 turns in an outer 100 sleeve 34 which is carried by a clamp or clip 35, said clip fitting laterally on the chassis

36 and being secured by bolts 37. The clips 35, at each side, with their sleeves 34, correspond in essentials with the clips 28 and sleeves 27, the details of one of said sleeves 5 being shown in Fig. 5, in which it will be seen that a transverse bolt 38, extending through the clip 35 and through the adjacent wall of the sleeve 34, serves to hold said sleeve in position. The head 38a of the bolt 10 38 has a swivel connection with the sleeve 34 and the connection is near the upper end of the sleeve, the swivel permitting a relative swinging movement of the clip 35 to dispose the sleeve vertically to aline with the lower 15 sleeve and properly receive the lamp rod 25 even though the position of the clip 35 on the chassis might not be perfectly vertical. The bolt 38 has a suitable nut 39 and, is necessary, a key 40 to prevent the nut from 20 turning. On the sleeve 31 at the top of the sleeve 34, a second collar 41 is secured to said sleeve 31 by a set screw.

With the described construction, the 25 pivots 19 permit of properly alining the link 20 and arm 22 without accuracy in the fitting of the parts and also a vertical vibration is permitted due to any slight relative vertical movements of the fixtures 14 and lamp rod 25. The telescoping connection, 30 between the lamp rod and the sleeve or tubular lamp support 31, accommodates the relative movement of the springs and chassis. Thus, a proper adjustment of the lamps is insured regardless of their turning movement with the knuckles and regardless of the 35 vibration of the vehicle parts. In addition to the simplicity and strength of the parts and the ease of adjustment, positive operation of the lamps is insured at all times.

40 Having thus described my invention I claim as new and desire to secure by Letters Patent:

1. A lamp - supporting and operating means of the class described including a fixture having means to secure the same to the knuckle-connecting rod of an automobile, a link connected at one end to said fixture by a horizontal pivot, an arm pivoted at its rear end to the opposite end of the said link 50 by a vertical pivot, an upright lamp rod to which the opposite end of said arm is secured, and elements in which the lamp rod is mounted to turn, said elements including means to secure the same in vertical alinement and respectively to a vehicle spring and to a vehicle frame.

2. A lamp - supporting and operating means including a fixture adapted for attachment to the knuckle-connecting rod of 60 an automobile to be moved by said rod, an upright lamp rod having connection with said fixture for turning said lamp rod by a movement of said fixture, and means including an upper and a lower sleeve adapted 65 for separate attachment to a chassis and to a

vehicle spring, in which sleeves the said lamp rod is adapted to turn, the said rod being vertically slidable in the upper sleeve.

3. A lamp - supporting and operating means including a fixture adapted for attachment to the knuckle-connecting rod of an automobile to be moved by the said rod, a vertical lamp rod, connections for turning said rod by a movement of said fixture, a clip adapted to laterally receive a vehicle 75 spring and having a sleeve thereon in which the lamp rod is adapted to turn, a clip adapted to laterally receive a frame member of an automobile and having a sleeve in which the lamp rod is adapted to turn, and 80 to slide, and means to secure said clips in position.

4. A lamp - supporting and operating means including a fixture adapted for attachment to the knuckle-connecting rod of 90 an automobile to be moved by said rod, an upright lamp rod, connections for turning said rod by a movement of said fixture, clips adapted for separate attachment to a chassis and to a vehicle spring respectively, 95 and sleeves swiveled to said clips, the said sleeves receiving the said lamp rod and permitting a turning movement of the rod on its axis.

5. A lamp - supporting and operating 100 means including an upright lamp rod, means connected with the lower end of said lamp rod and adapted to turn the same, the said rod having a round portion adjacent to its lower end, a sleeve embracing the said round portion of the lamp rod and in which sleeve the lamp rod is adapted to turn, means to secure said sleeve to a vehicle spring to move vertically with the movements of the spring, a second sleeve above the first sleeve and in 105 which the lamp rod is adapted to slide, said second sleeve having means engaging with the lamp rod to be turned by the latter, a third sleeve embracing the second sleeve and in which the second sleeve is adapted to turn, 110 and means to secure the third sleeve to a vehicle frame above the first sleeve.

6. A lamp - supporting and operating means including an upright lamp rod, means connected with the lower end of said lamp 115 rod and adapted to turn the same, the said rod having a round portion adjacent to its lower end, a sleeve embracing the said round portion of the lamp rod and in which sleeve the lamp rod is adapted to turn, means to secure said sleeve to a vehicle spring to move vertically with the movements of the spring, a second sleeve above the first sleeve and in 120 which the lamp rod is adapted to slide, a collar threaded on the lower end of the second sleeve, said collar and the adjacent portion of the lamp rod having mating vertical corrugations to permit a relative sliding of the lamp rod and cause a turning of the lamp rod to turn said corrugated collar and the 125 130

second sleeve, a third sleeve surrounding the second sleeve and in which the second sleeve is adapted to turn, means to secure the third sleeve to a vehicle frame above the first sleeve, and a collar on the second sleeve above the third sleeve.

5 In testimony whereof I have signed my

name to this specification in the presence of two subscribing witnesses.
